[57] CLAIM

The ornamental design for a combined tie rack and belt hanger, as shown and described.

DESCRIPTION

FIG. 1 is a perspective view of the combined tie rack and belt hanger, showing my new design, and taken from one side of same;

FIG. 2 is a perspective view thereof, taken from the opposite side of same;

FIG. 3 is a top view thereof;

FIG. 4 is a bottom view thereof;

FIG. 5 is a side elevational view thereof taken from the left side of FIG. 1; and

FIG. 6 is a side elevational view thereof, taken from the right side of FIG. 1.
